SIGNORS TO WESTINGHOUSE ELECTRIC AND MANUFACTURING COMPANY, A COR-
PORATION OF PENNSYLVANIA

CIRCUIT INTERRUPTER

Application filed September 27, 1928. Serial No. 308,719.

Our invention relates to circuit interrupters and more particularly to arc-extinguishing devices therefor.

One object of our invention is to provide an arc chute for a circuit interrupter that shall have a consumable material associated with the inner walls thereof adjacent to the arc path to prevent the condensation of the metallic vapors from forming a conducting deposit the full length of the walls of the arc chute.

Another object of our invention is to provide an arc chute that shall have a material that is not affected by the heat of the arc, inlaid in the portion of the walls opposite the point of greatest arc intensity.

A further object of our invention is to provide an arc chute with alternate sections of consumable and refractory material forming side walls that shall have the alternate sections so placed that the consumable material will at all times provide a clean insulating surface while the refractory material resists most of the burning and condenses most of the metallic vapor.

Heretofore arc chutes of refractory material for circuit interrupters were limited in their application due to the deposit of metal on the walls thereof adjacent to the arc path when employed on high voltage circuits. If a material were employed that would be consumed by the arc in order to carry away this deposit, the insulating qualities of the air or other gas, within the chute and immediately below it would be so reduced as to further limit its application.

It is the further object of our invention to combine these two types of materials in order to provide both the insulating qualities required for an arc chute and also to provide a means for preventing excessive deterioration and liberation of unburned combustible material from the walls adjacent the contact members.

These, and other objects that will be made apparent throughout the further description of our invention, are attained by the arc chutes hereinafter described and illustrated in the drawing, wherein:

Figure 1 is a view in sectional elevation il-

lustrating our improved switch mechanism;

Fig. 2 is a sectional view of the structure in Figure 1;

Fig. 3 is a view of a schematic arrangement of a particular embodiment of our improved switch mechanism;

Fig. 4 is a side elevational view of one section of the structure shown in Fig. 3.

Our invention comprises, in general, an arc chute 1 having side walls 2 and 3 built up from pieces of desired dimensions or molded from a material that has the desired insulating properties.

The arc chute 1 encloses the moving contact 6 and the stationary contact 7 that are positioned midway between or at one end of the side walls 2 and 3. The contact member 7 is attached to a fixed arm 8 by a bolt 9 and washers 11. The moving contact 6 is carried by a movable member 12 and is attached thereto by bolt 13 and washer 14. The members 12 and 8, together with the contacts 6 and 7, form the arc drawing members of a circuit interrupter not otherwise shown. 70

Referring to Figs. 1 and 2, the side walls 75 2 and 3 have openings 15 and 16 formed therein in which the projections 17 and 18 of refractory members 19 and 21 are held in fixed position. The members 19 and 21 are of considerable thickness and extend from 80 the inner surface of the side walls 2 and 3 to within close proximity of the sides of the contact members 6 and 7.

The side walls 2 and 3 of an arc chute disclosed in the copending application of A. L. 85 Van Emden, Serial No. 264,995, filed March 27, 1928, and assigned to the assignee of the present application, are composed of fibre or some other combustible substance upon which the metallic arc vapors will condense. The 90 surface of the walls are consumed by the arc and, the metallic deposit is freed and ejected from the arc chamber along with the consumed material and a clean surface free from the metallic condensation will be maintained 95 in the vicinity of the fuse terminals.

In applying the consumable material to circuit interrupters in which the main contact members are located in close proximity to the arcing contacts, it has been found that 100

a re-initiation of the arc may take place under certain conditions. Investigation shows that the combustible material, after becoming detached from the side walls, is 5 probably incompletely burned and, when it is carried into a region in which the atmosphere contains a large percentage of free oxygen, complete combustion thereof takes place. Such combustion tends to ionize the 10 air between points of different potential, and cause an electrical discharge to follow.

In order to obviate this difficulty, in one form of our invention as shown in Figs. 3 and 4, we mount upon the surface of the arc 15 chute walls, spaced sectional plates 19 and 21 made of an insulating material which does not carbonize when subjected to the high temperatures of the arc. The plates are spaced apart for the purpose of insulating 20 them from one another and to provide a deep crevice between them for preventing the metal vapors of the arc gas from reaching the surface of the fibre wall between the plates, the metal being condensed upon the plates 25 before it reaches the wall. In this manner, the arc chute walls in the vicinity of the contacts are provided with relatively small insulated sections upon which metal may be deposited without forming an extensive continuous conducting surface and the release 30 of combustible particles in the vicinity of the contacts is eliminated.

Another form of arc-chute, that is within the purview of the present invention and that 35 obviates the above noted difficulty, is that in which the members 19 and 21 are made of materials such as soap-stone, chalk, plaster of Paris and the like. These materials may be consumed in a greater or less degree, by 40 the action of the arc, but they do not char and produce glowing particles. The material is slowly eroded by the action of the arc and the disintergration of the surface prevents the objectionable deposit of metal from 45 forming on the walls of the arc-chute. The metal is carried out of the arc chute by the eroded material, which does not burn and liberate ionizing gases.

It has been found that most of the burning 50 takes place directly adjacent to the contacts just after they separate and that substantially all of the metal vapors are liberated during the initial formation of the arc. We take advantage of this localized burning and 55 vaporization in the structure shown in Figs. 1 and 2 and provide the single members 19 and 21 that are made of refractory material and extends some distance from the arc-chute walls directly adjacent to that part of 60 the arc path where the arc is initially formed. Metal volatilizing from the electrodes 6 and 7 condenses on the surface of the extended members immediately after it is 65 vaporized and very little, if any, deposit is formed on the side walls 2 and 3. It is to be

understood that the refractory material may be erodable in order that the condensing metal particles may be carried away with the eroded material in the manner described.

While we have described and illustrated but 70 two embodiments of our invention, it will be apparent to those skilled in the art that various modifications, substitutions, changes, omissions and additions may be made in the apparatus herein described and illustrated 75 without departing from the spirit and scope of our invention as set forth in the appended claims.

We claim as our invention:

1. The combination with a circuit inter- 80 ruptor having separable arcing contact members and an arc chute associated with said members having the walls thereof made of a consumable but relatively highly refractory material that is disintegrated slowly at its surface by the arc incident to separation of the contacts whereby metal vapors condensing on the surface are carried away by the particles released by distintegration, of a plate 85 of insulating material disposed flat-wise between the contact members and the said walls having higher refractory characteristics than the walls for protecting the walls in the immediate vicinity of the arc from the intense heat thereof and for condensing thereon the 90 metal vapor in the arc.

2. The combination with a circuit inter- 95 ruptor having separable arcing contact members and an arc chute associated with said members having the walls thereof made of a 100 consumable but relatively highly refractory material that is disintegrated slowly at its surface by the arc incident to separation of the contacts whereby metal vapors condensing on the surface are carried away by the particles released by disintegration, of a plu- 105 rality of spaced insulating plates having higher refractory characteristics than the said walls and disposed flat-wise between the contact members and the said walls and in spaced 110 relation to constitute interrupted surfaces for protecting the walls in the immediate vicinity of the arc from the intense heat thereof and for condensing thereon the metal vapors in 115 the arc.

3. The combination with a circuit inter- 120 ruptor having separable arcing contact members and an arc chute associated with said members having the walls thereof made of a consumable but relatively highly refractory 125 material that is disintegrated slowly at its surface by the arc incident to separation of the contacts whereby metal vapors condensing on the surface are carried away by the particles released by disintegration, of a plate of insulating material disposed flat-wise beside the contact members and along the said walls and in the immediate vicinity of said contact members, said insulating material having higher refractory characteristics than 130

the walls for eliminating excessive burning of the walls in the immediate vicinity of the arc by the intense heat thereof and for condensing thereon the metal vapor in the arc.

- 5 4. The combination with a circuit interrupter having separable arcing contact members and an arc chute associated with said members having walls of a consumable but relatively highly refractory material that is
- 10 disintegrated slowly at its surface by the arc incident to separation of the contacts of a plate of insulating material having higher refractory characteristics than said walls disposed flat-wise beside and in the immediate
- 15 vicinity of the contact members for a portion only of the wall bounding the path of movement of the contact members whereby the surface of said arc chute between the contact members when separated is partly of consumable material and partly of highly refractory material with the highly refractory material positioned where the heat of the arc is of greater intensity.
- 20

In testimony whereof, we have hereunto
25 subscribed our names this 15th day of September, 1928.
